UNITED STATES PATENT OFFICE.

JOHN E. GILSON, OF PORT WASHINGTON, WISCONSIN, ASSIGNOR TO GILSON MANUFACTURING COMPANY, OF PORT WASHINGTON, WISCONSIN, A CORPORATION OF WISCONSIN.

FRICITION-CLUTCH.

1,081,528.

Specification of Letters Patent.

Patented Dec. 16, 1913.

Application filed June 10, 1912. Serial No. 702,784.

To all whom it may concern:

Be it known that I, JOHN E. GILSON, a citizen of the United States, residing at Port Washington, in the county of Ozaukee and 5 State of Wisconsin, have invented a Friction-Clutch, of which the following is a full and complete specification.

My invention is an improvement in friction-clutches, and relates more especially to 10 that particular class in which a split ring or band carried by the driving-wheel is clamped for frictional engagement with a drum keyed to the operating-shaft, whereby to connect said wheel to the shaft for rotation therewith.

The primary object of my present invention is to provide a particular form of mechanism for applying the friction ring or band, such mechanism being strong and durable in construction and effective in use to insure a positive operation of the clutch device; all as hereinafter fully described in the specification and specifically set forth in the appended claims.

25 In the accompanying drawings: Figure 1 is a side view of a friction-clutch, constructed in accordance with my invention. Fig. 2 is a longitudinal vertical sectional view through the clutch. Fig. 3 is a rear end view of the clutch. Fig. 4 is a detail view of the split ring or band, the upper part being broken away to show the means employed for contracting said ring or band. Fig. 5 is a face view of the wheel which 30 carries the split ring or band.

Like numerals of reference indicate like parts in all the figures of the drawings.

In carrying out my invention the driving-shaft, as 7, to which the friction-clutch is applied, is preferably reduced in diameter at its outer end, as shown in Fig. 2, and upon this shaft is mounted a long sleeve 8, which is securely fixed to said shaft in any suitable manner, for instance at its front and rear ends by a pin 9 and key 10, respectively. The rear end of the sleeve is enlarged to form a friction-drum 8^a, and at a suitable distance from the drum said sleeve is reduced in diameter to provide two stepped bearing portions 8^b and 8^c, adapted to receive the operating parts hereinafter described.

50 Mounted upon the drum 8^a, so as to frictionally engage therewith, is a split ring or band 11 having two pairs of ears 11^a and

11^b, by which it is connected to a wheel 12, loosely mounted on the bearing portion 8^b of the sleeve, said pairs of ears being at opposite sides of the ring or band, and the pair of ears 11^a located at one side of the 60 transverse cut or split 11^c in the ring to receive a spindle or rocking-shaft 13 which coöperates with a sliding-bolt 14 for contracting the ring or band, said bolt extending from a lug, 15, on the ring at the opposite side of the transverse cut or split therein. The spindle or rocking-shaft is carried by the wheel 12, being mounted in a long bearing 12^a at one side of the same, and passing through the ears 11^a of the split 70 ring or band serves to connect the latter to said wheel. To hold the split ring or band on the end of the spindle or rocking-shaft the latter is provided with a transverse pin 16 at its outer end, and to more securely 75 connect the ring to the wheel a pin 17 is passed through the ears 11^b at the other side of the ring and through an opening 12^b in the wheel, said wheel being preferably reinforced at this point by bosses which surround the opening at the opposite ends thereof, as shown in the drawings.

For the purpose of operating the sliding-bolt the spindle or rocking-shaft 13 is provided with a longitudinal groove forming a 85 shoulder 13^a, with which engages a corresponding shoulder, 14^a, on the bolt, the last-mentioned shoulder being formed by cutting away or notching the bolt at one side, and in order to maintain the sliding-bolt in positive engagement with the spindle or rocking-shaft a pin 18 is passed transversely through the pair of ears 11^a immediately above said bolt. It will be seen by reference to Figs. 3 and 4 of the drawings that when the spindle or rocking-shaft 13 is turned to the right the bolt will draw one end of the split-ring toward the other; that is to say, will draw the end carrying the lug 15 and bolt toward the end which is supported on the wheel 12 by the spindle, and this operation will contract the ring or band upon the drum so as to frictionally engage therewith, according to the power applied to the spindle or rocking-shaft. The spindle or shaft is rocked only a certain distance by the operating means, hereinafter described, and in order to regulate the frictional engagement of the clutch-surfaces the sliding-bolt is adjusted by means of nuts 19 threaded on the outer 110

end thereof against the lug 15, it being understood, of course, that the bolt passes loosely through said lug.

For the purpose of operating the spindle 5 or rocking-shaft the forward end thereof projects beyond the bearing 12^a and has keyed thereon an operating-arm 20, the outer end of which is disposed in the path of a sliding-cone 21, mounted on the reduced bearing-portion 8^c of the sleeve 8, and for 10 the purpose of manipulating this cone it is provided with a hand-wheel 22, secured thereon by a collar 23. At the upper end of the cone, just beyond the inclined surface 15 face thereof, is a peripheral groove 21^a, to receive the outer end of the arm, or friction-roller 24 thereon, and maintain the parts in this relative position. The cone is loosely mounted on the sleeve so that it will not turn 20 therewith during the operation of sliding it back and forth to operate the arm 20, in applying and releasing the friction-clutch, and it will be noted that the movement of the sleeve in applying the clutch is limited 25 by contact with a shoulder, as 8^d, formed by the enlarged bearing-portion 8^b of the bearing-sleeve 8.

The wheel 12, which carries the split ring or band is provided with a long hub, by 30 which it is mounted on the bearing-portion 8^b of the bearing-sleeve, and said wheel is held in place by means of a collar 25. The wheel 12 may constitute the driving-wheel for transmitting the rotary motion of the 35 shaft, but in the present instance the rim of this wheel is narrow, and is provided with apertures 12^c, suitably spaced and adapted to receive the means for fastening thereto a ring, as 26, (dotted lines in Figs. 40 1 and 2), having peripheral teeth to form a gear-wheel, or of sufficient width to form a pulley.

In Fig. 1 the parts are shown in their relative position when the clutch is applied, 45 the arm being swung outward with its free end engaging the groove 21^a at the outer portion of the sliding cone, and the spindle 13 turned to exert tension on the bolt to clamp the split-ring tightly upon the friction-drum 8^a, and when so arranged the 50 wheel 12 and split-ring turn with the drum and shaft by reason of the frictional engagement of the split-ring with said drum. In releasing the clutch it is only necessary to 55 grasp the hand-wheel 22 and move it outward until the sliding-cone carried thereby releases the arm 20, which latter will then swing inward toward the sleeve and relieve the tension on the bolt thus permitting the 60 split ring or band to expand out of frictional engagement with the drum. This

will permit the sleeve 8 and driving-shaft 7 to which it is connected to revolve freely within the split-ring, wheel 12, and sliding-cone, and the gearwheel 26 will then remain 65 stationary.

Having thus described my invention, I claim:

1. In a friction-clutch, the combination with the driving-shaft, of a drum fixed 70 thereon and having a bearing-sleeve at one side of the same, a split-ring on the drum to frictionally engage the same, said split-ring having a pair of apertured ears on one end and a lug on the other end, apertured ears 75 on the split-ring opposite the aforesaid ears and lug, a wheel mounted on the bearing-sleeve and having a long bearing on a line with the apertured ears at one of the adjoining ends of the split-ring, a pin projecting from the wheel through the other apertured ears of the split-ring, a rocking-shaft in the aforesaid bearing on the wheel rotatable in the adjoining ears of the split-ring and having a shoulder between said ears, 80 a bolt extending from the lug on the split-ring and having a shoulder with which the shoulder on the rocking-shaft co-operates, and means for operating the rocking-shaft. 85

2. In a friction-clutch, the combination 90 with the driving-shaft, of a drum fixed thereon and having a bearing-sleeve at one side of the same, a split-ring on the drum to frictionally engage therewith, said split-ring having a pair of apertured ears on one 95 end and a lug on the other end, apertured ears on the split-ring opposite the aforesaid ears and lug, the ring being cut transversely on a line with the center of the last mentioned ears, a wheel mounted on the bearing-sleeve and having a long bearing on a line with the apertured ears at the end of the split-ring, a pin connecting said wheel with the apertured ears hereinbefore last mentioned, a rocking-shaft in the aforesaid bearing on the wheel rotatable in the adjoining ears at one end of and having a shoulder between said ears on the split-ring, a bolt extending from the lug of the split-ring and having a shoulder with which the shoulder on the rocking-shaft co-operates; together 100 with an arm projecting from the other end of the rocking-shaft, and a sliding cone on the sleeve engaging the outer end of the arm, substantially as shown and described. 105

In testimony whereof I have signed my name to this specification in the presence of two subscribing witnesses.

JOHN E. GILSON.
